UNITED STATES PATENT OFFICE.

GEORGE CROMPTON, JR., OF WORCESTER, MASSACHUSETTS, ASSIGNOR TO ROBERT C. PRATT, OF WORCESTER, MASSACHUSETTS.

SHUTTLE-CHANGING MECHANISM FOR LOOMS.

Application filed September 25, 1922. Serial No. 590,512.

To all whom it may concern:

Be it known that I, GEORGE CROMPTON, Jr., a citizen of the United States, residing at Worcester, in the county of Worcester 5 and Commonwealth of Massachusetts, have invented a new and useful Improvement in Shuttle-Changing Mechanism for Looms, of which the following, together with the accompanying drawings, is a specification.

10 My invention relates to shuttle changing mechanism for looms of the so-called narrow ware type, in which a plurality of spaced shuttles are adapted to be driven back and forth in unison with respect to a plurality of spaced groups of warp threads in order to simultaneously weave a number of separate strips of narrow fabric, such for example, as tape or ribbon. My invention relates more particularly to that class of narrow 15 ware looms familiarly known as "double deck," wherein two sets of fabrics are simultaneously woven one above the other, thus enabling one loom to weave twice as many fabrics as are woven on a single deck loom 20 having the same frontage.

In my copending application, Serial No. 504,869, filed October 3, 1921, there is shown and described an improved shuttle changing mechanism for narrow ware looms, by means 25 of which the shuttles may be changed either individually, or collectively, on any desired pick of the loom without interrupting the operation of the same, and in my copending application, Serial No. 567,719, filed June 30, 1922, there is shown and described a 30 shuttle changing mechanism of the same general type as set forth in the first mentioned application, with the additional provision of means whereby the entire mechanism 35 may be caused to operate automatically to bring about a transfer of shuttles after the latter have made a predetermined number of picks.

The object of the present invention is to 40 provide an improved shuttle changing mechanism embodying the same general principles of operation as disclosed in my above mentioned co-pending applications, whereby the shuttles of a double deck narrow 45 ware loom may be changed after the shuttles in each deck have been exhausted to a predetermined degree. The above and other advantageous features of my invention 50 will hereinafter more fully appear, refer-

ence being had to the accompanying drawings in which—

Fig. 1 is a view in front elevation of a portion of a double deck loom provided with a shuttle changing mechanism embodying my invention.

Fig. 2 is a vertical sectional view along the line 2—2, Fig. 1.

Fig. 3 is a vertical sectional view along the line 3—3, Fig. 1.

Fig. 4 is an enlarged plan view showing an upper shuttle holder.

Fig. 5 is an enlarged plan view showing an intermediate shuttle holder.

Fig. 6 is a vertical sectional view along the line 6—6 of Fig. 5.

Like reference characters refer to like parts in the different figures.

Referring first to Figs. 1 and 2, a portion of the lay of a loom is indicated at 1, and has mounted thereon two sets of shuttle carriers 2 and 5 arranged one above the other and adapted to be moved back and forth in unison by means of the usual toothed racks in engagement with pinions adapted to drive the carriers. The lower 70 set of carriers 2 are adapted to operate between lower race blocks 3 and intermediate race blocks 4, while the upper set of carriers 5 are adapted to operate between the intermediate race blocks 4 and upper race 75 blocks 6. The rack for driving the lower carriers 2 is indicated at 8, and the rack for driving the upper carriers 5 is indicated at 7. The several spaces between the tiers of race blocks 3, 4 and 6 are each occupied by lower and upper groups of warp threads 80 9 and 10, which are connected to the loom harnesses in such a manner as to constitute interlocking sheds, arranged one above the other, through which the respective sets of shuttle carriers 2 and 5 are to be driven back and forth.

As best shown in Fig. 4, every other upper block 6 is provided with a shuttle holder 11, the details of which form no part of the present invention, but are fully shown and described in the above mentioned copending application, Serial No. 504,869. Each holder 11 is adapted to coact with end plates 12 provided on a shuttle 13, to hold the shuttle in position against movement in a substantially horizontal plane, and at the same time to permit the shuttle to be moved ver-

tically. Each of the carriers 2 and 5 is provided with a device for engaging and holding a shuttle 13 as it is moved downwardly, whereby the shuttle is firmly held in position on the carrier. As fully set forth in the above mentioned copending application, Serial No. 504,869, each of such devices consists of coacting rigid and resilient portions mounted on the shuttle and carrier respectively, and it is not believed necessary to further describe the same herein.

As best shown in Figs. 5 and 6, every other intermediate block 4 is provided with a pair of lugs 14, spaced apart by a distance substantially equal to the overall length of a shuttle 13, and provided with grooves 15 for receiving the end plates 12 of the shuttle 13. A latch 16 is mounted on each lug 14 and extends to a point below the groove 15 so as to yieldingly support the end plate 12 of the shuttle 13 in the groove 15, the latch 16 being adapted to yield upon the application of a downward force to the shuttle 13.

25 A transerrer 17 is provided above each shuttle holder 11 and is carried on an operating rod 18, slidably mounted on the lay 1. Up and down movement is adapted to be imparted to the rod 18 by means of a bell crank lever 19 operated by a plunger 20. As fully set forth and described in my above mentioned copending application, Serial No. 567,719, the plunger 20 is adapted to be automatically operated to cause the transerrer 17 to be moved downwardly to bring about a transfer of shuttles 13 after a given set of shuttles have made a predetermined number of picks, as will be hereinafter referred to.

40 Every other lower block 3 is provided with a pair of stops 21 for limiting the downward movement of a shuttle 13 as it is positioned in the lower carrier 2 by the transerrer 17. As fully set forth and described in my above mentioned copending application, Serial No. 504,869, the stops 21 are normally held clear of the lowermost shuttle 13, so that the latter may be ejected from its carrier 2 upon downward movement of the transerrer 17. The stops 21 are, however, adapted to be projected outwardly far enough to limit downward movement of a new shuttle entering the carrier 2 at the end of the downward movement of the actuating rod 18.

55 Every other one of the blocks 3, 4 and 6 is provided with a pair of rollers 22, 23 and 24 respectively, for the purpose of lining up the shuttles 13 horizontally on the carriers 2 and 5. As a set of shuttles 13 are moved by the carriers 2, they pass between sets of rollers 22 and 23 which tend to properly align the shuttles on the carriers and therefore correct any misalignment which may have occurred, due to the vibration of the

loom. The shuttles 13 on the carriers 5 are similarly alined by the action of the rollers 23 and 24.

In the operation of double deck narrow 70 ware looms, it may be desired to run the different sets of shuttles in either the same, or in opposite directions. In case the shuttles should be operated in the same direction, it is obvious that the rollers 23 on the intermediate blocks 4 would have turning moments applied thereto in opposite directions, and that the rollers 23 would turn in the direction of the greatest moment. This action would not offset the alining of the shuttles by the rollers 23, as the rollers are 75 not used solely for the purpose of reducing friction, but rather in order to distribute the wear between the shuttles and the rollers over as great a surface as possible. Consequently, it is more or less immaterial 80 that the intermediate rollers 23 are, at times, turned first in one direction and then in another.

Having thus described the various parts 85 entering into my invention, the operation 90 thereof is as follows:—Let it be assumed that the loom is first operated with full shuttles in the upper carriers 5 and the holders 11, and that the mechanism controlling the operation of the transerrer 17 is so set 95 as to cause operation of the transerrer 17 when substantially one-half the filling on the active shuttles has been run out. Upon the operation of the transerrer 17, the partially exhausted shuttles will be ejected 100 from the carriers 5 and the fresh shuttles from the holders 11 substituted therefor. The partially exhausted shuttles will then be held between the lugs 14 on the intermediate blocks 4 by the latches 16. The loom 105 will continue to operate as before until substantially one-half of the filling in the fresh shuttles in the carriers 5 has been exhausted, whereupon the transerrers 17 will again operate to insert fresh shuttles from the holders 11 to the carriers 5. When this occurs, the partially exhausted shuttles on the intermediate blocks 4 will be inserted in the lower carriers 2, the latches 16 yielding 110 upon the application of downward pressure 115 by the transerrer 17.

Both sets of carriers 2 and 5 will then 120 be operating with active shuttles, so as to simultaneously weave two sets of fabrics by cooperation of the warp threads 9 and 10, the upper carriers 5 operating with substantially 125 fresh shuttles, while the lower carriers 2 operate with shuttles having substantially one-half of the filling run out. When the transerrers 17 next operate, it is 130 obvious that the shuttles on the carriers 2 will have been substantially exhausted, and that these shuttles will be ejected and allowed to fall into the discharge passages 25. which are provided in the lay 1, as described 135

in my above mentioned copending application, Serial No. 567,719.

From the foregoing, it is apparent then that with my improved shuttle changing mechanism as described above, the loom will continue to weave two sets of fabrics so long as the holders 11 are provided with fresh shuttles following each operation of the transferrers 17. Any given set of shuttles inserted in the holders 11 will first be operated by the upper carriers 5, and upon the exhaustion of substantially one-half of the filling thereon, will be automatically transferred to the carriers 2 for running off the remainder of the filling after remaining on the intermediate blocks 4 a period equal to the intervals between the operations of the transferrers 17.

While I have shown my invention as being embodied in a double deck narrow ware loom, that is, a loom employing two sets of active shuttles arranged one above the other, it is obvious that it may as well be employed in connection with looms adapted to simultaneously weave more than two sets of fabrics. If, for example, it should be desired to employ my shuttle changing mechanism in connection with a triple deck or quadruple deck loom, it would only be necessary to so arrange the mechanism for operating the transferrers so as to cause them to be operated after the shuttles in the top-most carriers have been either one-third or one-fourth exhausted. Various other modifications may be carried out without departing from the spirit and scope of my invention, and I desire therefore that only such limitations be imposed thereon as may come within the scope of the appended claims.

40 I claim—

1. In a loom, a lay, on said lay two series of shuttles, one series being superimposed upon the other series, and means for replenishing the weft simultaneously in each series.

2. In a loom, a lay, a set of carriers on said lay located one above the other, shuttles held by said carriers for weaving a plurality of fabrics one above the other, spare shuttles carried on said lay, and a transerrer cooperating with said spare shuttles to move said spare shuttles into said carriers.

3. In a loom, a lay, a set of carriers on said lay located one above the other, shuttles

held by said carriers for weaving a plurality of fabrics one above the other, and a transerrer to eject said shuttles from said carriers.

4. In a loom, a lay, a set of carriers on said lay located one above the other, shuttles with different degrees of filling exhaustion held by said carriers for weaving a plurality of fabrics one above the other, and a transerrer to move said shuttles with respect to said carriers.

5. In a loom, a lay, a plurality of shuttle carriers operatively connected to said lay one above the other, a plurality of shuttles to fit in said carriers, and a transerrer to cause a given shuttle to operate first in one carrier and then in another.

6. In a loom, a lay, a plurality of shuttle carriers operatively connected to said lay one above the other, a plurality of shuttles to fit in said carriers, and a transerrer to cause a given shuttle to operate first in one carrier until a given degree of filling exhaustion is obtained and later to operate in another carrier.

7. In a loom, a lay, a plurality of shuttle carriers operatively connected to said lay one above the other, shuttle holders, a plurality of shuttles, and transferring means to cause said shuttles to move from holders to carriers and from carriers to holders and to be ejected, in a predetermined progression.

8. In a loom for simultaneously weaving a number of separate fabrics one above the other, a carrier for operating a shuttle to weave one fabric until a predetermined degree of filling exhaustion is obtained, another carrier, and transerrer means for placing said shuttle in said other carrier to weave a different fabric.

9. In a loom, a plurality of shuttle carriers operating one above the other and carrying shuttles, spare shuttles above each of said carriers, all of said shuttles being adapted to be moved in unison, thereby ejecting the lowermost shuttle.

10. In a loom, a plurality of shuttle carriers operating one above the other and carrying shuttles, spare shuttles above each of said carriers, and means for moving all of said shuttles in unison to eject the lowermost shuttle.

Dated this 19th day of September, 1922.
GEORGE CROMPTON, JR.
